(57) **CLAIM**

The ornamental design for a support for poultry breasts, as shown and described.

DESCRIPTION

FIG. 1 is a first perspective view of a support for poultry breasts showing our new design;

FIG. 2 is a second perspective view thereof;

FIG. 3 is a top plan view thereof;

FIG. 4 is a left side view thereof, with the right side being a mirror image; and,

FIG. 5 is a front view thereof.

The broken lines showing portions of the article form no part of the claimed design.

1 Claim, 3 Drawing Sheets
